(57) **CLAIM**

The ornamental design for a LED track luminaire, as shown and described.

DESCRIPTION

FIG. 1 is a perspective view of a LED track luminaire in accordance with the present design;

FIG. 2 is a front view thereof, wherein a rear view is the mirror image;

FIG. 3 is a second side view thereof taken ninety degrees from the front view, wherein a second side view is a mirror image thereof; and,

FIG. 4 is a top view thereof.

The broken lines in the drawings illustrate portions of the LED track luminaire that form no part of the claimed design.
